CULTIVATOR

Filed Aug. 15, 1928

UNITED STATES PATENT OFFICE

JOHN C. KOCH, OF PETERSBURG, NEBRASKA

CULTIVATOR

Application filed August 15, 1928. Serial No. 299,756.

The present invention is directed to improvements in cultivators, and more particularly to a cleaner therefor.

The primary object of the invention is to provide a cleaner so constructed that it can be conveniently attached to the cultivator fender for removing obstructions, such as stalks and weeds, which become lodged on the shovels.

10 Another object of the invention is to provide a device of this character so constructed that the obstructions lodged upon the shovels will be removed as the cultivator is traveling across the field.

15 A still further object of the invention is to provide a device of this character which is extremely simple in construction, efficient in operation, and one which can be manufactured at a very small cost.

20 With these and other objects in view, this invention resides in the novel features of construction, formation, combination and arrangement of parts to be hereinafter more fully described, claimed and illustrated in 25 the accompanying drawing, in which:—

Figure 1 is a side elevation of the device.

Figure 2 is a top plan view.

Figure 3 is a sectional view on line 3—3 of Figure 1.

30 Referring to the drawing, 1 designates the beam of a conventional form of two row cultivator, the rear end of which is curved downwardly and has fixed thereto the usual shovels 2.

35 A clamp 3 is fixed to the innermost beam of the cultivator and serves to securely hold the forward end of a bar 4 clamped to the beam. The bar 4 is offset laterally with respect to the beam 1 and extends diagonally 40 across the rear face of a rectangular sheet metal fender 5, and to which it is secured in any approved manner, said bar having a bearing 6, the purpose of which will appear later.

45 The cleaner comprises a hub 7 having a plurality of radial arms 8 formed integral therewith, the free ends of which are pointed, as at 9, in order that they will more readily penetrate the earth. The hub is provided 50 with a reduced axle 10 which rotatably en-

gages a bearing 11 formed in the fender 5 and the bearing 6 formed in the bar 4. This axle is threaded as at 12, for receiving the nut 13. It will thus be seen that the axle is rotatably mounted in order that when the 55 cultivator is drawn across the field the hub can freely rotate as the pointed ends of the arms successively penetrate the earth.

Frequently stalks and weeds will be caught between a pair of the shovels, thus retarding the free movement of the cultivator.

It has heretofore been necessary to stop the cultivator and remove these obstructions. This objection is eliminated by the application of the cleaner, since it will be obvious 65 that as the cultivator is in motion rotary movement will be imparted to the cleaner and the arms 8 will force and lift the obstructions from between the shovels in order that it will not be necessary to stop the cultivator 70 when the shovels become clogged.

While the device is primarily designed for use in connection with two row cultivators, it will be of course understood that it is not limited to such use, since it will effectively 75 operate in connection with a single row cultivator.

From the foregoing it is thought that the construction, operation and many advantages of the herein described invention will 80 be apparent to those skilled in the art, without further description and it will be understood that various changes in the size, shape, and proportion and minor details of construction, may be resorted to without departing from the spirit or sacrificing any of 85 the advantages of the invention.

What is claimed is:—

1. The combination with a cultivator including a beam and shovel, of a bar secured to the beam and having its fixed end offset laterally and extended rearwardly and downwardly in spaced relation to the shovel, said bar being provided with a bearing, a 90 fender secured to the bar and provided with a bearing registering with the bearing in the bar, and a cleaning device mounted for rotation on the inner face of the fender and including a hub having arms radiating 95 therefrom, said hub being provided with an 100

axle mounted for rotation in the bearings and provided with a threaded terminal, and a nut engaging the threads on the axle and bearing against the bar.

5. 2. The combination with a cultivator including a beam and shovel, of a bar secured to the forward portion of the beam and having its fixed end offset laterally and extended rearwardly and downwardly in spaced relation to the shovel, a substantially rectangular fender plate secured to the inner face of the bar, said bar and fender plate being provided with alined bearings, and a cleaning device mounted for rotation on the inner face of the fender and including a hub having arms radiating therefrom and provided with pointed terminals, said hub being provided with a reduced axle fitting within the alined bearings, and a fastening device engaging the axle and bearing against the outer face of the bar.

In testimony whereof I affix my signature.

JOHN C. KOCH. [L. S.]
